US0D1009632S

(12) **United States Design Patent** (10) **Patent No.:** **US D1,009,632 S**
(45) **Date of Patent:** **** Jan. 2, 2024**

(54) **BOTTLE**

(71) Applicant: **Exal Corporation**, Youngstown, OH (US)

(72) Inventor: **Thomas Chupak**, Youngstown, OH (US)

(73) Assignee: **Exal Corporation**, Youngstown, OH (US)

(**) Term: **15 Years**

(21) Appl. No.: **29/686,485**

(22) Filed: **Apr. 4, 2019**

(51) LOC (14) Cl. **09-03**

(52) U.S. Cl. USPC **D9/500**
CPC **B21D 22/28** (2013.01)

(58) **Field of Classification Search**

USPC ..... D9/434, 435, 436, 438, 439, 440, 441, D9/445, 447, 448, 449, 450, 500, 501, D9/502, 503, 504, 505, 516, 537, 538, D9/539, 540, 541, 542, 543, 544, 545, D9/549, 550, 551, 552, 560, 563, 572, D9/573, 574, 575, 715, 719, 738; D7/300, 300.1, 509, 510, 511, 523, 608 CPC B21D 22/28; B21D 51/26; B21D 51/2615; B29C 49/54; B29D 23/001; B65D 1/00; B65D 1/0207; B65D 1/0276; B65D 1/0223; B65D 1/023; B65D 1/0246; B65D 1/40; B65D 23/00; B65D 23/001; B65D 23/102; B65D 41/04; B65D 79/0084; B65D 81/00; B65D 2501/00; B65D 2501/0009; B65D 2501/0081; F25D 3/08; Y10S 215/00; Y10S 264/918
